(57) **CLAIM**

The ornamental design for a collapsible tick removal tool, as shown and described.

DESCRIPTION

FIG. 1 is a front perspective view of a collapsible tick removal tool, showing my new design in a retracted position;

FIG. 2 is a top perspective view of FIG. 1;

FIG. 3 is a left-side elevational view of FIG. 1;

FIG. 4 is a right-side elevational view of FIG. 1;

FIG. 5 is a front elevational view of FIG. 1;

FIG. 6 is a rear elevational view of FIG. 1;

FIG. 7 is a top plan view of FIG. 1;

FIG. 8 is a bottom plan view of FIG. 1;

FIG. 9 is a front perspective view thereof, illustrated in an expanded configuration;

FIG. 10 is a top perspective view of FIG. 9;

FIG. 11 is a left-side elevational view of FIG. 9;

FIG. 12 is a right-side elevational view of FIG. 9;

FIG. 13 is a front elevational view of FIG. 9;

FIG. 14 is a rear elevational view of FIG. 9;

FIG. 15 is a top plan view of FIG. 9;

FIG. 16 is a bottom plan view of FIG. 9; and,

FIG. 17 is an exploded perspective view thereof.
